UNITED STATES PATENT OFFICE.

CESARE BARBIERI, OF NEW YORK, N. Y., ASSIGNOR TO THE VORTEX MFG. CO., OF CHICAGO, ILLINOIS, A CORPORATION OF ILLINOIS.

CUP-MACHINE CARTON-LOADING ATTACHMENT.

Application filed May 3, 1924. Serial No. 710,750.

This invention relates more particularly to a flat cup counting and carton loading attachment for use in connection with a flat cup forming machine of a type illustrated and described in my pending application for patent for a "flat paper cup forming machine", filed March 15, 1924, Serial No. 699,424. The present invention pertains to an attachment connected with the flat cup stacking mechanism of a flat cup forming machine, said attachment adapted to be operated from the machine to automatically mark off the stack of flat cups at predetermined intervals whereby a certain number of flat cups may be readily separated from the remainder of the stack of cups and be lifted into a carton engaged on the upper ends of flexible upright slats or cup retaining springs forming part of the cup stacking magazine.

It is an object of this invention to provide a flat cup forming machine with an attachment for the cup stacking device whereby a marking mechanism is adapted to act at a predetermined time to mark off cups in selected quantities for insertion into cartons which are adapted to be slipped onto the cup stacking device.

It is also an object of the invention to provide a flat cup forming machine with a mechanism operable from the machine and having means whereby a marking device is caused to be operated at selected intervals to mark cups at predetermined intervals so that a counted number of the cups may be readily separated from a stack for insertion into a carton.

It is furthermore an object of the invention to provide a flat cup forming machine with a stacking mechanism adapted to have cartons engaged thereon in position to receive flat cups in predetermined quantities the number of which is determined by a marking device connected with the stacking mechanism and operable from the machine.

It is an important object of this invention to provide a cup forming machine wherein a cup stacking mechanism is provided with an improved automatic counting device having a marker which acts at predetermined times to apply a mark on the last one of a selected number of counted cups so that the required quantity of cups may be readily removed from the stacking mechanism and

elevated into a carton engaged on the stacking mechanism.

Other and further important objects of this invention will be apparent from the disclosures in the specification and the accompanying drawings.

This invention (in a preferred form) is illustrated in the drawings and hereinafter more fully described.

On the drawings:—

Figure 1 is a top plan view of a flat cup making machine provided with a cup stacking mechanism having a cup counting device embodying the principles of this invention.

Figure 2 is a front elevation of the machine taken on line 2—2 of Figure 1.

Figure 3 is an enlarged fragmentary top plan view of the cup stacking end of the machine with the cup stacking magazine removed.

Figure 4 is an enlarged detail view taken on line 4—4 of Figure 1 with parts omitted.

Figure 5 is a detail view taken on line 5—5 of Figure 1.

Figure 6 is an enlarged fragmentary detail section taken on line 6—6 of Figure 5 with parts in elevation.

Figure 7 is a detail view taken on line 7—7 of Figure 6.

Figure 8 is a vertical view of the cup stacking end of the machine.

Figure 9 is an enlarged detail view taken on line 9—9 of Figure 8 with parts omitted.

Figure 10 is a detail section taken on line 10—10 of Figure 9.

Figure 11 is a fragmentary detail section taken on line 11—11 of Figure 8.

Figure 12 is a similar sectional view with parts omitted, showing the operation of the cup carrying slide bars.

Figure 13 is a top plan view of the cup stacking magazine.

Figure 14 is a fragmentary detail section taken on line 14—14 of Figure 13.

Figure 15 is an enlarged fragmentary detail section taken on line 15—15 of Figure 13.

Figure 16 is an elevational view of the cup stacking magazine having a carton engaged on the upper portion thereof ready to be filled with cups.

As shown on the drawings:—

The reference numeral 1 indicates a machine frame having journalled thereon in suitable bearings a main driving shaft 2

provided with a flywheel 3 adapted to be driven from any suitable source of power. Fixed on the drive shaft 2 is a sprocket gear around which a drive chain 4 is trained. The chain 4 is connected to drive a clutch mechanism designated as a whole by the reference numeral 5. The clutch 5 is adapted to be controlled by means of a handle 6 which when operated actuates a starting shaft 7 whereby a yoke carrying pins 8 acts to shift a clutch collar 9. The clutch mechanism 5 may also be operated by means of a hand-wheel 10.

Mounted on one end of the machine frame 15 is a cup blank feed magazine 11. A blank feed reel 12 is provided beneath the magazine 11 and is adapted to be operated from a gear 13 fixed on the clutch carrying shaft 14. The gear 13 meshes with a gear 15 mounted on a shaft 16. The shaft 16 also has mounted thereon a gear 17 and a bevel gear 18. The gear 17 meshes with a gear 19 on the shaft of the blank feed reel 12. Blank guide posts 20 are mounted upon the 25 magazine 11.

Mounted on the front end of the shaft 16 is a wheel or disk 21 having an eccentric pin 22 thereon on which one end of an eccentric rod or bar 23 is engaged. The eccentric bar 23 is pivotally supported near its other end on a pin 24 carried on the lower end of a link 25 which is fixed on a pin 26 carried by a slidable block 27. The block is slidable in a slot 28 provided in the front of the 35 machine frame 1. An extension arm 29 is integrally formed at an angle on one end of the bar 23. Pivotally connected to the end of the arm 29 is one end of a connecting rod 30 the other end being pivotally connected 40 to the upper end of the outer arm of a double arm lever 31. The lower end of the lever 31 is pivoted on a bracket 32 secured on the machine frame 1.

A bar 33 is connected with the slidable block 27 and has mounted thereon a blank advancing plate 34 which extends into the path of the advancing cup blanks. A blank gripper mechanism 35 is also carried by the bar 33. A cup blank carrying carriage 36 50 is provided on the bar 33 and has a cup blank centering flange formed thereon.

When a cup blank is fed out of the cup blank holding magazine it is delivered onto a stationary table 37 provided with a raised 55 curved stop edge 38. A stationary table 39 is provided and is separated from the table 37 by a diagonal opening or slot 121 in which a pair of separated upper and lower blank folding bars 40 are adapted to operate.

A cup blank is adapted to be gripped by the gripper mechanism 35 and is carried over the table 37-39 into a position over the folding bars 40. A glue applying 65 mechanism 41 is operable from a cam shaft

42 which has a beveled gear 43 thereon meshing with the bevel gear 18 to receive a drive therefrom. The glue applying mechanism is adapted to apply a dab of glue to the under surface of the advanced cup 70 blank.

When the gripper mechanism 35 is advanced into position to grip the next cup blank the blank feed plate 34 is in its advance position over the stationary table 37 75 and above a portion of the advanced cup blank. Just previous to the time that the gripper mechanism starts to move away from the cup blank magazine the blank folding bars 40 are operated by a cam wheel 80 43 which is driven by the cam shaft 42. The folding bars 40 are thus raised through the table opening 39 and act to bend up a portion of the advanced cup blank while the other portion of the cup blank is held in 85 place by the feed plate 34.

As the gripper mechanism engages the next blank and starts to move away from the blank holding magazine 11 the blank feed plate 34 moves through the slot between the bars 40 thereby causing the upturned portion of the first cup blank to be folded over against the top surface of the feed plate 34.

As the partially folded cup blank is advanced by the feed plate 34 a second glue applying mechanism 44 operable by the cam wheel 43 acts to apply a strip of glue to a margin of the cup blank. As the strip of glue is being applied to a margin or flap of 95 the cup blank, the cup blank is advanced into the field of operation of a flap folding mechanism operable from a cam 45 on the cam shaft 42. The glued flap is thus folded over against the body of the partially 100 formed cup. A cup feed cam 46 operable by a gear train 47 now acts to advance the partially formed cup as the feed plate 34 starts to move back toward the blank holding 105 magazine 11.

A cup tip bending device 48 is operable by a cam 49 which receives a drive through meshing bevel gears 50 and 51. The beveled gear 51 is mounted on the end of the cam shaft 42. The cup tip bending device 48 110 acts to bend over the tip of the cup and at the same time the feed cam 46 engages the cup and advances the same thereby causing the cup tip to be bent upwardly against the underside of the body of the cup so that the 115 spot of glue applied by the glue mechanism 41, acts to glue the tip to the cup body thereby completing the forming of the flat cup 53 (Figure 3).

The cup is advanced by the feed cam 46 between a pair of feed rollers 52 which press the glued parts together and at the same time advance the cup 53 over onto a table extension 54. Secured on the end of the machine frame 1 is a casting 55 having an 120

extending arm 56 on which a carriage 57 is slidably engaged. A stop 58 is fixed on the end of the arm 56. The carriage 57 is provided with a vertical slot in which a plate 59 is slidably engaged. Integrally formed at right angles to the upper edge of the slide plate 59 is a horizontal plate 60 which extends transversely beneath the table extension 54. Secured to the bracket plate 60

10 on opposite sides of the table extension 54 are a pair of slide bars 61 recessed at 62 leaving upturned hooks or fingers 63. The hooks 63 are slightly curved to conform to the curvature of the curved open end of the 15 flat cup 53. A cup pocket is thus provided in the slideable cup removing bars 61 which slide between guides 64 and 65 fastened to the casting 55.

15 Mounted upon the guides 64 and 65 is a 20 cup holding and stacking magazine base section 66 having a substantially triangular shape and having guide slots 67 therein (Figure 4) through which the bars 61 are adapted to slide and be raised. Secured to 25 the magazine base section 66 are a plurality of upright posts 68 supporting an upper magazine section 69 similar in shape to the lower section 66. Secured to the inner 30 surface of the lower magazine section 66 and extending upwardly through the upper magazine section 69 are a plurality of flexible slats or cup retaining springs 70 over which a cup carton 71 (Figure 16) is adapted to be engaged so that a stack of counted 35 flat cups 53 may be delivered upwardly into the carton.

The slide plate 59 is provided with a key slot 72 (Figure 9) through which a stub shaft 73 projects. The shaft 73 is supported in a bearing 74 formed on the carriage 57. Secured on the outer end of the stub shaft 73 is a bell crank 75 having a cam block 76 engaged on the inner side of the short arm of the bell crank. The bell 45 crank block 76 projects into the slide plate slot 72 to permit raising and lowering of the slide plate 59 with respect to the carriage 57. The long arm of the bell crank 75 is pivotally connected to one end of a 50 link 77. The other end of the link 77 is pivoted to the inner arm of the double arm lever 31 (Figure 8). The bars 61 are first advanced toward the feed rolls 52 to permit the formed flat cup 53 to drop into the bar recesses 62 after which the bars are raised 55 and then retracted to deliver the cup into the stacking magazine underneath the stack of cups already formed and stacked.

The beveled gear 50 is mounted on one 60 end of a shaft 78 journaled in bearings 79 (Figure 4) on the machine frame. Secured on the shaft 78 is a sprocket 80 with which an endless chain 81 is engaged. The chain 81 is also engaged around a sprocket 82 (Figure 5) which is mounted on a worm

shaft 83 supported in a bearing bracket 84 forming part of a bearing casting 85 secured to the machine frame. A bracket or arm 86 is also integrally formed on the casting 85. Formed or fixed on the shaft 83 70 is a worm 87 which meshes with a worm wheel 88 engaged on a shaft 89 journalled in a bearing 90 on the casting 85. Also fixed on the shaft 89 is a small gear or pinion 91 (Figure 8) which meshes with a 75 large gear 92 on a shaft 93. The shaft 93 is journalled in a bearing 94 formed on the casting 85.

A shaft or pin 95 is supported in a bearing 96 on the bracket 86. Pivoted on the 80 shaft 95 is the one end of an arm 97 to which one end of a spring 98 is engaged. The spring 98 is coiled around the bearing 96 and is secured thereto to hold the arm 97 in a raised position. A roller 99 is 85 rotatably mounted on the arm 97 and has rolling contact with the peripheral edge of a cam disk 100 having a notch 101 in the periphery thereof. The disk 100 is mounted on the shaft 89 to the outside of the small 90 gear 91. Pivoted on the free end of the arm 97 is the lower end of a lever 102 having a roller 103 rotatably mounted thereon for co-action with the peripheral edge of a cam disk 104 having a notch 105 in the 95 periphery thereof. The cam disk 104 is supported on the shaft 93 to the outside of the gear 92.

Pivoted on the upper end of the lever 102 is a bifurcated end of a pin 106. The pin 106 is slidably in a collar or sleeve 107 integrally formed on the lower end of an arm 108 which is integrally formed on a sleeve 109. The sleeve 109 is rotatable on a pin or shaft 110. Also integrally formed 105 on the sleeve 109 is an upwardly extending arm 111 which is engaged against a plate spring 112. The plate spring 112 is secured on a bracket 113 mounted on the casting 55.

Projecting transversely through the upwardly directed arm 111 is a pencil sleeve 114 tapered at one end and open at the other end. Disposed within the pencil sleeve 114 is a marking lead 115 the point of which projects through the tapered end of the pencil sleeve 114. A pencil feed screw 116 is threaded into the open end of the pencil sleeve 114 (Figure 6) and is adjustable by means of a head 117. The marking end of the pencil 114 projects into an opening 118 in the guide 65 and into the lower portion of the cup magazine base section 66 to mark the lowermost cup 53 at predetermined time intervals. Fixed on the under the side of the plate 60 is a flange 125 of a spring plate 118 offset at 119 and having the lower corners 120 bent at an angle.

The operation is as follows:—
A stack of cup blanks is placed between the magazine guide posts 20 with the lower- 130

most blanks disposed within the magazine base 11. A drive is imparted to the fly-wheel 3 from any suitable source of power. By operating the control handle 6 the clutch mechanism 5 is operated and a drive is transmitted by the chain 4 to the shaft 14 and to the blank feed reel 12. The feed reel 12 is so constructed that at a predetermined time in each revolution thereof pads on said feed reel are brought into contact with the lowermost cup blank in the magazine 11. The lowermost cup blank is thus fed out of the magazine base section 11 onto the raised portion of the table 37.

With the delivery of a cup blank from the magazine the disk 21 actuates the eccentric bar 23 and the link 25. The lower gripper jaw of the gripper mechanism 35 is moved into open position. The slidable block 27 is advanced by the action of the eccentric bar 23 so that the open gripper mechanism is moved into position ready to grip the advanced cup blank. With the continued rotation of the disk 21 the gripper mechanism is closed to grip the cup blank, after which the block 27 starts to move away from the magazine 11. The cup blank is pulled over the table sections 37 and 39 and over the lowered bars 40.

The gripper mechanism 35 is now opened to release the advanced cup blank as the block 27 again starts to move toward the magazine 11. The feeder plate 34 is moved over the top of the cup blank as the flange 35 on the carriage 36 acts to push the cup blank back against the raised edge 38 of the table 37 to properly center the cup blank. The glue applying mechanism 41 is now operated from the cam shaft 42 and acts to apply a dab of glue to the under surface of the centered cup blank.

The cam wheel 43 now acts to raise the bars 40 to bend up a portion of the cup blank along one edge of the feed plate 34. As another blank is gripped by the gripper mechanism the block 27 starts to move toward the cup stacking end of the machine and the feed plate 34 acts to draw the cup blank between the raised bars 40 to bend over the upturned portion of the cup blank. As the cup blank is folded and advanced the second glue applying mechanism 44 is operated by the cam wheel 43 to cause a strip of glue to be applied to a margin of the cup blank.

The glued margin of the cup blank is next creased and bent upwardly after which the cam 45 on the cam shaft acts to operate a flap folding mechanism whereby the glued margin of the cup blank is bent over against the body of the cup. The partially formed cup is advanced further by the feed plate 34 into a position wherein the tip of the partially completed cup projects over an edge 65 of the table section 39. The cam 49 on the

shaft 78 now acts to operate the cup tip bending device 48 which bends the tip of the cup.

With the movement of the block 27 toward the magazine 11 the cup feed plate 34 moves out of the partially formed cup and the cup feed cam 46 engages the flat cup to feed the same between the feeding rolls 52. As the cup is advanced by the feed cam 46 the bent over tip of the cup is bent upwardly against the cup body so that the dab of glue will cause the tip to adhere to the body of the flat cup.

The cup feed rolls 52 now act to advance the completed flat cup over onto the table extension 54. The flat cup drops by gravity into the pocket 62 of the cup removing bars 61. The bars 61 are advanced by the carriage 57 which is slidable on the guide bar 56 by the action of the inner lever arm 31 and the link 77 which are connected by the connecting rod 30 to the end of the arm 29 on the eccentric bar 23. As the carriage 57 starts to move outwardly toward the cup stacking end of the machine the bell cranks 75 is first actuated to swing the short arm of the bell crank 75 upwardly so that the block 76 (Figure 9) acts to raise the plate 59 thereby elevating the bars 61. These bars being positioned beneath the cup stacking magazine 66 act to raise the stack of formed cups already stacked within the stacking magazine. As the carriage 57 moves outwardly the raised bars 61 slide from under the raised stack of cups carrying a formed cup in the pocket 62 into the base section 66 of the stacking magazine beneath the stack of cups already stacked therein. The stack of cups drops into the pocket 62 upon the cup just delivered. The bars 61 are again lowered as the carriage 57 reaches the end of its outward movement on the bar 56.

The flat cups being formed follow one another in constant succession through the machine and are automatically delivered one at a time into the bottom of the stacking magazine and are elevated each time a new cup is added to the bottom of the stack. The flat cups thus pile up in the stacking magazine between the guides 70.

The shaft 78 receives a drive from the cam shaft 42 through the beveled gears 50 and 51. The chain 81 is thus driven and acts to rotate the worm 87 the worm wheel 88 and the shaft 89. The disk 100 and the pinion 91 are rotated with the shaft 89. The pinion 91 being in mesh with the gear 92 rotates the same thereby causing a drive to be transmitted to the shaft 93 and the disk 104 (Figure 8). When the rollers 99 and 103 are in the positions illustrated in Figure 8 the plate 118 carried by the carriage plate 60 reciprocates over the top of the sleeve 107 and over the upper end of the

retracted pin 106. The gears 92 and 91 are of different size and of a selected gear ratio so that with each revolution of the large gear 92 the small gear 91 rotates a number of times.

When the notch in the disk 100 registers with the roller 99 no movement of the arm 97 takes place because the roller 103 on the lever 102 is in contact with the peripheral edge of the disk 104. At predetermined times the notch 105 in the disk 104 registers with the roller 103 at the same time that the notch 101 in the disk 100 is brought into register with the roller 99. At such a time the spring 98 acts to swing the arm 97 upwardly thereby moving the lever 102 upwardly. The pin 106 on the upper end of the lever 102 is projected upwardly through the sleeve 107 into the position shown in Figure 6. As the carriage 57 moves outwardly the plate 118 is brought into contact with the pin 106 and swings the arm 108 from the full line position of Figure 6 into the dotted line position. This operation causes the upwardly extending arm 111 to swing inwardly thereby causing the tip or point of the pencil lead 115 to make a mark on the lowermost cup in the magazine 66. The gears 91 and 92 and the disks 100 and 104 are so arranged that the pencil will be operated automatically at predetermined intervals so that the cups are counted and marked at intervals.

When the notch 105 moves out of engagement with the roller 103 the pin 106 is retracted and the spring 112 acts to move the pencil or marker into the full line position of Figure 6.

A cup carton 71 may be engaged over the upwardly projecting ends of the spring guides 70 with the open lower end of the carton resting on the upper magazine section 69 so that a counted number of flat cups may be pushed upwardly into the carton. The carton is removed and closed and contains a counted number of flat cups. The pencil marks on the stack of cups in the stacking magazine are readily discernible so that cartons may be easily filled with a selected number of flat paper cups.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. The combination with a cup stacking magazine, of mechanisms for lifting the cups stacked in the magazine and delivering cups to the magazine beneath the cups stacked therein, and means adapted to mark off the stacked cups in predetermined numbers in the magazine.

2. The combination with a flat cup stacking magazine, of a reciprocating carriage, means for operating the same, and mechanisms carried by the carriage and operable by said means for raising cups in the magazine and then delivering formed cups upwardly into the bottom of the magazine beneath the raised cups. 70

3. The combination with a cup stacking magazine, of a carriage, means connected to reciprocate the carriage, a slidable plate on the carriage, mechanisms connected with the plate to operate the same, and cup delivering members supported on said plate adapted to carry cups and deliver the cups into the stacking magazine. 75

4. The combination with a cup stacking magazine, mechanisms for raising the cups stacked therein, means for delivering cups into the bottom of the magazine below the raised stack of cups, and a mechanism for counting off the cups delivered into the magazine. 85

5. The combination with a cup holding magazine, of means for raising the stack of cups in the magazine and then sliding another cup beneath the raised stack, and a marking device for marking off predetermined quantities of the cups in the magazine. 90

6. The combination with a cup stacking magazine, of a cup delivering means, a mechanism for operating the same to cause cups to be delivered upwardly into the magazine, a cup counting device connected with the magazine, and means for operating the counting device to count off predetermined quantities of the cups in the magazine. 95

7. The combination with a cup stacking magazine, of means for automatically raising the cups in the magazine and delivering cups beneath the raised cups, a marking device, and means for causing the marking device to operate at predetermined times to mark off the cups in predetermined quantities in the magazine. 105

8. The combination with a cup holding magazine, of a cup delivering means, an eccentrically operated device connected to operate said cup delivering means to cause the same to deliver cups into the magazine and elevate the cups therein, a plate carried by the cup delivering means, a marker, a slidable control pin supported thereon, and mechanisms adapted at predetermined times to move the pin into the path of movement of said plate to automatically cause the marker to make marks on the stack of cups in the magazine at predetermined intervals. 115

9. The combination with a cup stacking magazine, of a cup delivering means, driving means therefor to cause the delivering means to deliver cups into the magazine and gradually raise the stack of cups in said 120

- magazine, a member carried by the cup delivering means, a pivoted arm, a marker carried thereon and positioned to project into the magazine, a pin slidable in said pivoted arm, control means for governing the operation of said pin, and means adapted to operate the control means to cause the same to move the pin at predetermined times into the path of operation of said member to swing the pivoted arm and cause the marker to make marks at spaced intervals on the stack of cups. 10
10. The combination with a cup stacking magazine, of a cup delivering means, driving means therefor to cause the delivering means to deliver cups into the magazine in stacked relation, a member carried by the cup delivering means, a fulcrumed arm, a marker supported on one end thereof positioned to project into the magazine, a pin slidable in the other end of said fulcrumed arm, a spring controlled pivoted arm, a lever pivoted thereon and supporting said pin, a roller on said arm, a roller on said lever, notched disks co-acting with said rollers, and means for operating said disks to cause movement of said pin into the path of operation of said member at predetermined times to swing the fulcrumed arm and cause the marker to make marks at spaced intervals on the stack of cups in the magazine. 20
11. The combination with a magazine, of means adapted to be raised and then shifted for delivering and moving cups upwardly in the magazine, and a marker adapted to place marks on the stacked cups at intervals to designate counted quantities of cups. 30
12. The combination with a cup stacking magazine, of means for delivering cups transversely and then upwardly into the magazine, a cup marker, and means for automatically operating the marker to mark off the cups in the magazine. 40
13. The combination with a cup stacking magazine, of means for automatically delivering and elevating cups therein, a fulcrumed arm, a pencil sleeve supported thereon, a marker in said sleeve and projecting therefrom, means for adjusting the marker, a slidable member engaged in said arm, a reciprocating device, and a mechanism for moving the slidable member into the path of said reciprocating device at predetermined times to operate said arm to cause the marker to mark off cups in predetermined quantities in said magazine. 50
14. The combination with a cup stacking magazine, of reciprocating means for delivering cups thereto, mechanisms for raising the reciprocating means at predetermined times to raise cups in the magazine, a cup marker, a mechanism carried by the reciprocating means, and means connected with the marker adapted to be moved into the path of said mechanism to cause operation of the marker at predetermined times. 60
15. The combination with a cup stacking magazine, of reciprocating means for delivering cups thereto, a plate carried by the reciprocating means, a cup marker, a slid- 70 able member coacting therewith, spring controlled toggles connected with said member, rollers on said toggles, notched disks coact- ing with said rollers, and gear means for operating said notched disks to cause the same to bring the notches thereof into register with said rollers to permit the spring controlled toggles to move the slidable member into the path of said plate to cause oper- 80 ation of the marker. 85
16. The combination with a stacking mag- azine, of a carriage, a recessed plate slidable on the carriage, cup delivering and stacking bars supported on said plate, a bell-crank supported on said plate, a block on said bell-crank projecting into the recessed plate, and a mechanism connected with said bell-crank to reciprocate the carriage and cause the bars to deliver cups from the machine into 90 the magazine and then elevate the cups therein. 95
17. The combination with a stacking mag- azine, of a carriage, a recessed plate slidable on the carriage, cup delivering bars sup- 100 ported on said plate, a block on said bell crank projecting into the recessed plate, a pivoted lever, a link connecting the lever with the bell crank, and an eccentric mech- anism connected to actuate the lever to cause reciprocation of the carriage and operation of said plate and bars to deliver cups into the magazine. 105
18. The combination with a cup holding magazine, of recessed bars having sliding engagement therewith, and mechanisms adapted to first raise the bars to elevate cups in said magazine and then slide said bars to deliver a cup into the magazine beneath the raised cups. 110
19. The combination with a cup stacking magazine, of recessed bars having sliding engagement therewith, a support, a carriage slidable thereon, a plate slidable on the carriage and supporting said bars, and means connected with the plate to operate the plate and carriage to cause the bars to first elevate a stack of cups in said magazine and then deliver a cup into the magazine beneath the raised stack of cups. 115
20. A cup stacking device comprising a magazine adapted to have a carton engaged thereon, a mechanism for automatically delivering cups into the magazine, and means for marking off the cups in counted num- 120 bers to permit a selected number of cups to be readily moved from the magazine into the carton. 125
21. A stacking machine comprising a cup magazine adapted to have cartons removably 130

engaged thereon, means for automatically delivering cups into the magazine, and a device adapted to mark off the cups in the magazine in predetermined quantities to permit the cartons to be readily filled with a predetermined number of said cups from said magazine. 10

22. A cup stacking device comprising a magazine, a carton holder on the top

thereof, means for automatically delivering cups upwardly through the bottom of the magazine, and means for automatically marking off the cups to permit a selected number of cups to be raised into a carton on said carton holder. 15

In testimony whereof I have hereunto subscribed my name.

CESARE BARBIERI.
